Robert W. Bixby
ATTORNEY.

UNITED STATES PATENT OFFICE.

CATHERINE M. LANGHORNE, OF PLAINFIELD, NEW JERSEY.

WALL FIXTURE.

1,426,574.

Specification of Letters Patent. Patented Aug. 22, 1922.

Application filed January 11, 1922. Serial No. 528,403.

To all whom it may concern:

Be it known that I, CATHERINE M. LANGHORNE, a citizen of the United States, residing at Plainfield, in the county of Union and State of New Jersey, have invented certain new and useful Improvements in Wall Fixtures, fully described and represented in the following specification and the accompanying drawing, forming a part of the same.

This invention relates to wall fixtures, and aims to provide a convenient support for various kitchen utensils, doing away with the necessity of shelves for this purpose.

An object of the invention is to provide hooks for the support of saucepans and similar articles combined with means for supporting the covers of these articles in compact vertical arrangement, thus eliminating the necessity for the shelf space which would otherwise be necessary for the covers when the saucepans are hung up.

A further object of the invention is to form the wall fixture of a series of interchangeable units thus facilitating the manufacture of the fixture and making it possible to increase the capacity of the fixture at any time by merely adding more units.

A further object of the invention is to provide for telescoping together the component units of the wall fixture so that the fixture may be placed in compact form for shipment.

A fourth object of the invention is to provide for economical manufacture of the fixture by forming each unit so that it may be made of a single continuous piece of wire.

In order that the invention may clearly be understood, I will describe in detail the specific embodiments of it illustrated in the accompanying drawings, in which:

Fig. 1 is a perspective view of a wall fixture embodying the invention, arranged in operative position upon a sheet metal back-
ing;

Fig. 2 is a sectional side elevation taken on the line 2—2 of Fig. 1 and showing the fixture secured directly to the wall; and

Fig. 3 is a perspective view of the fixture arranged for shipment.

In the form shown in the drawings, the fixture consists of a series of units of which three, A, B, C are shown in Figs. 1 and 3. It will be understood that the fixture may

consist of any desired number of units, it being usually desirable to use more units than are illustrated in the drawings.

Each of the units is formed of a single continuous piece of wire. The wire is bent so as to form a spacing loop 10, a substantially vertical rack member 11, a hook 12, and connecting members 13 and 14 by which the rack member 11 and the hook 12 are respectively joined with the spacing loop 10.

The spacing loop 10 is most desirably formed to lie in a single plane. It may be conveniently given the form of a right triangle as shown, the ends of the loop being near the right angle corner thereof. The upper side 15 of the loop 10 is preferably extended so as to form a small attachment loop 16 providing means for securing the unit to a wall. The ends of the loop 10 are extended outwardly transversely to the plane of the loop to form the connecting members 13 and 14 which lie adjacent to each other. From the outer end of the connecting member 13 the wire extends to form the substantially vertical rack member 11. A short spring loop 17 is preferably formed between the outer end of the connecting member 13 and the rack member 11. A small hook 18 may be formed at the upper end of the rack member 11. From the outer end of the connecting member 14 the wire extends downwardly to form the hook 12.

The units constructed as described are interlocked by passing the bite 19 of the spacing loop 10 of one unit, for example, the unit B, around the connecting members 13 and 14 of the next unit, for example, the unit A. This is accomplished by passing the bite 19 of the unit B over the upper end of the rack member 11 of the unit A and then drawing the bite 19 down along the rack member 11 until it strikes the connecting member 13. The loop 10 is then passed around the loop 17 and the hook 12 so that the bite 19 embraces the connecting members 13 and 14 of the unit A, as shown in Fig. 1.

When all the units which are to form the fixture have been interlocked in the manner described, the fixture may be secured to the wall by means engaging the loop 16 of each unit and one additional fastening means engaging the bite 19 of the end unit A. The fastening means may consist of screws passing through the loops 16 and the bite 19 of the unit A so that the fixture is secured di-

rectly to the wall as illustrated in Fig. 2. The fastening means shown in Fig. 1, however, is sometimes more desirable. This consists of a sheet metal backing 20 provided with tabs 21 cut from the backing and positioned to engage the loops 16 and the bite 19 of the unit A. The backing 20 may be secured to the walls by screws 22 at its corners.

10 When the fixture is applied to a wall by either type of fastening means, each unit has a three-point support provided by the fastening means secured to the loop 16, the engagement between the bite 19 of its spacing loop 10 and the connecting members of the next unit and the engagement of the lower corner 23 of its loop 10 with the wall. The entire fixture therefore is firm and rigid and is not displaced by placing articles upon it.

15 20 The fixture forms a convenient support for all the utensils customarily used in a kitchen. Some of the articles which may be supported by the fixture are indicated in dotted lines in Fig. 1. Thus saucepans are 25 hung on the hooks 12 by means of the holes 30 in their handles 31, while the covers 32 of the saucepans are placed vertically in the rack formed by the rack members 11. The edges of each cover rest upon the connecting members 13 and 14 of a pair of units while the body of the cover is held against the wall by the rack members 11. Owing to the presence of the spring loop 17 the rack members 11 may be bent outwardly from the 30 wall to facilitate the insertion and removal of the covers, while inward pressure of the rack members retains the covers tightly against the wall after they have been inserted.

35 40 After the units have been interlocked together in the manner previously described, and before they are secured to the wall, they may be telescoped together as illustrated in Fig. 3 by drawing the bite 19 of the spacing loop 10 of each unit toward that of the next unit. After shipment the units may be placed in operative position by merely drawing them apart until the bite 19 of the spacing loop 10 of each unit engages the connecting members 13 and 14 in the next unit.

45 50 From the above description it is apparent that the invention provides a compact and convenient support for all kitchen utensils, which may be given any desired capacity, and may be manufactured at small cost.

55 I wish it clearly understood that my invention is by no means limited to the specific embodiment of it which I have illustrated and described.

60 65 What I claim is:

1. A wall fixture, consisting of a series of interlocked units each comprising a substantially vertical rack member, a connecting member extending transversely from the rack member near the lower end thereof,

and a spacing member extending from the inner end of the connecting member and in a plane transverse thereto and engaging the connecting member of the next unit.

2. A wall fixture consisting of a series of 70 interlocked units, each comprising a substantially vertical rack member, a connecting member extending transversely from said rack member near its lower end, and a spacing loop extending from the inner end 75 of said connecting member in a plane transverse thereto and embracing the connecting member of the next unit.

3. A wall fixture consisting of a series 80 of interlocked units, each formed of a single continuous piece of wire providing a substantially vertical rack member, a connecting member extending transversely from the rack member near the lower end thereof, and a spacing loop extending from the inner 85 end of the connecting member in a plane transverse thereto and embracing the connecting member of the next unit.

4. A wall fixture consisting of a series 90 of interlocked units, each formed of a single continuous piece of wire providing a substantially vertical rack member, a spring loop at the lower end thereof, a connecting member extending from said spring loop transversely to the rack member, and 95 a spacing loop extending from the inner end of the connecting portion in a plane transverse thereto embracing the connecting member of the next unit.

5. A wall fixture consisting of a series 100 of interlocked units each formed of a single continuous piece of wire providing a spacing loop secured to the wall and extending substantially parallel thereto, a first connecting member extending outwardly from one end of said loop, a rack member extending upwardly from the outer end of said first connecting member, a second connecting member extending outwardly from the other end of said loop and adjacent to said first connecting member, and a hook extending downwardly from the outer end of said second connecting member, the bite of the spacing loop of each unit embracing the two connecting members of the next unit. 115

6. A wall fixture consisting of a series 120 of interlocked units each formed of a single continuous piece of wire providing a spacing loop secured to the wall and extending substantially parallel thereto, a first connecting member extending outwardly from one end of said loop, a rack member extending upwardly from the outer end of said first connecting member, a hook at the upper end of said rack member, a second connecting member extending outwardly from the other end of said loop and adjacent to said first connecting member, and a hook extending downwardly from the outer end of said second connecting member. 125

member, the bite of the spacing loop of each unit embracing the two connecting members of the next unit.

7. A wall fixture for supporting articles, 5 consisting of a series of interlocked units each comprising a closed loop adapted to be secured to the wall, a connecting member extending outward from the loop near one of its ends, and an article supporting member 10 extending transversely from the outer end of the connecting member, the connecting member of each unit extending through the loop of the adjacent unit and being 15 slideable therein.

8. A wall fixture consisting of a series

of interlocked units each comprising a loop adapted to be secured to the wall, a first connecting member extending outwardly from one end of the loop, a second connecting member extending outwardly from the other end of the loop and lying adjacent to said first connecting member, the two connecting members of each unit extending through the loop of the adjacent unit being slideable therein and being provided at their outer ends with means engaging the outer side of said loop.

In testimony whereof I have hereunto set my hand.

CATHERINE M. LANGHORNE.
